THERAPEUTIC DISPENSER FOR VOLATILE SUBSTANCES

Application filed May 10, 1930. Serial No. 451,264.

The primary purpose and object of my invention is to provide a therapeutic device for general use that may be used for the volatilizing of medicated substances for the treatment 5 and prevention of contagious diseases.

The invention in its preferred embodiment consists of a one-piece body element having a hollow interior and having an enlarged cup-shaped recess disposed at the discharge outlet, into which a carrying agent may be placed. A removable plug is placeable within one side of the body element having electric terminals disposed therein and so arranged that the terminal ends will be spaced 10 apart and terminate in close spaced relationship with the void disposed within the body element to thereby evaporate and volatilize substantially the full content of fluid placed therein. The device is adapted for being 15 heated electrically upon its inner side.

The primary object of my invention is to provide a simple and inexpensive device adapted for being heated electrically and which may be used for the heating of fluids 20 and liquids placed within a void that is disposed within the body element.

A further object of my invention consists in providing a simple, efficient and inexpensive device that may be used for the treating 25 and prevention of contagious diseases.

A still further object of my invention consists in providing a one-piece body element, made of porcelain, that may be used for electrically evaporating medicated fluids that 30 may be placed within the body of the device, or that may be placed within the carrying agent placed within the cup container.

With these and incidental objects in view, the invention consists in certain novel features of construction and combination of parts, the essential elements of which are set forth in the appended claims, and a preferred form of embodiment of which is hereinafter 35 shown with reference to the drawings which accompany and form a part of this specification.

In the drawings:—

Fig. 1 is a side elevation of the assembled 40 device.

Fig. 2 is a longitudinal, sectional, side view of the assembled device.

Fig. 3 is a perspective, end view of the electric plug and the terminals outwardly extending therefrom, the points of which are 45 adapted for being placed in close spaced relationship with the inner portion of the base of the device.

Fig. 4 is a top, plan view of the mechanism 50 illustrated in Fig. 1.

Like reference characters refer to like parts throughout the several views.

I preferably form the body 1 of my device of porcelain or other refractory material, or any suitable material, having a base 2 that is 55 circular in contour and having a void 3 disposed within the body element. A cup-shaped recess 4 is disposed at the upper end of the body element. A carrying agent, made of any suitable material, as felt or other 60 fibrous or suitable material, is placeable within the cup-shaped top, the same being illustrated at 5. The carrying agent is placed within the cup, into which medicated substances may be placed for the treatment 65 and prevention of contagious diseases. The fluid placed within the void may also be medicated and when evaporated releases the medicated substance also.

The contour of the body element is shaped 70 to permit a diffusion of and to make the steam which is to come into contact with the carrying agent 5 possess the same qualities as is possessed by live or dry steam and therefore be able to absorb a greater amount of the 75 medicate substance with which the carrying agent is permeated than is normally possible with the former types of vaporizers. The body element has a ceiling 1A which is inclined upwardly toward the opening 4A that 80 connects the main body portion with the cup-shaped recess 4. Bends 2A and 2B are disposed upon the oppositely disposed sides of the body element. Humps 3A and 3B are 85 also disposed upon the oppositely disposed sides of the body element with hump 3A above bend 2A and hump 3B below bend 3A. These 90 bends and humps all have a two-fold purpose, namely, to allow and assist the user to grip the device with comfort, and also to present 95 100

greater surface area to the steam that is being or is to be developed within the inside of the body element.

An electric plug 6 is placeable within the plug receiving boss 7, that outwardly extends from the rear of the body element. The plug is placed within the plug receiving boss and is cemented therein through the use of any binding or cementitious material 8 to form 10 a relatively tight, leak-proof connection between the plug and the boss.

An electric conductor 9 conducts electricity into the plug from a source of electric energy not here shown. A pair of electric terminals 15 10 and 11 inwardly extend from the plug and to which the electric conductor is attached. The electric terminals 10 and 11 are spaced apart sufficiently to form a gap and the ends 20 12 and 13 curve downward and are so shaped that the ends may be placed in spaced relationship with the inner surface 14 of the base of the body element. The inner surface 14 is preferably made concave in order that the heat developed within the electric terminals 25 25 will evaporate practically the entire contents of the fluid being placed within the body element. The electric conductor 9 preferably terminates in a threaded socket 15 to adapt the same to a connection with the ordinary 30 30 lamp socket with which the same is adapted for being connected and from which the source of electric energy is secured.

While the form of mechanism herein shown and described is admirably adapted to fulfill 35 the objects primarily stated, it is to be understood that it is not intended to confine the invention to the one form of embodiment herein shown and described, as it is susceptible 40 of embodiment in various forms, all coming within the scope of the claims which follow.

What I claim is:—

1. An electric liquid vaporizing device comprising a one piece container, inwardly extending bends disposed at oppositely disposed sides of the container, a hump disposed on each side of the container, one above and one below the bends, a cup-shaped recess terminating the discharge end of the container, 45 a plug receiving boss rearwardly extending from the container, an electric plug adapted for placement within the plug receiving boss, a cementitious binder disposed between the plug and the plug receiving boss to render 50 the joint liquid tight, an electric conductor disposed within the plug and electric terminals outwardly extending from the inner end of the plug, the electric terminals being 55 spaced apart and terminating in spaced relationship with the inner bottom wall of the container, and a carrying agent disposed 60 within the cup-shaped recess.

2. A device of the class described comprising a one piece body element the inner wall of its base being sloped downwardly to a com-

mon center, inwardly extending bends and outwardly extending humps disposed upon oppositely disposed sides of the body element, said bends and humps adapted to increase the surface area within the body element and also serve to form a grip for the device, a plug receiving boss outwardly extending from the rear wall of the body element, an electric plug adapted for placement within the boss, means for rendering the meeting surfaces between the plug and the boss liquid tight, electric terminals inwardly extending from the electric plug having curved inner ends placed to terminate in spaced relationship with the center of the base of the body element, and a cup terminating the discharge end of the body element.
